(57) **CLAIM**

The ornamental design for a reusable ornament base, as shown and described.

DESCRIPTION

FIG. 1 is a front view of a reusable ornament base; the rear view being a mirror image;

FIG. 2 is a right side view; the left side view being a mirror image thereof;

FIG. 3 is a top view thereof; and,

FIG. 4 is a bottom view thereof.

The broken lines in the drawings depict environmental subject matter that forms no part of the claimed design.

The four embodiments shown depict slight variations in the reusable ornament design. Such embodiments involve a single inventive concept.
